UNITED STATES PATENT OFFICE.

JOSEPH B. RUATTI, OF LOS ANGELES, CALIFORNIA.

SAFETY-RAZOR-BLADE-SHARPENING DEVICE.

Application filed April 15, 1922. Serial No. 553,150.

To all whom it may concern:

Be it known that I, JOSEPH B. RUATTI, a citizen of Austria, residing at Los Angeles, in the county of Los Angeles and State of California, have invented new and useful Improvements in Safety-Razor-Blade-Sharpening Devices, of which the following is a specification.

This invention relates to a device for 10 sharpening safety razor blades and the like.

An object of the invention is to provide a small, compact and portable machine for sharpening razor blades of the safety razor type in which the blades are of substantially 15 rectangular form and of thin flexible steel and may have one or more razor edges. Another object is to provide a manually operable razor blade sharpening machine. A further object is to provide a machine constructed of standard parts for operating one 20 type of blade, as for instance a double edged blade and which machine can be constructed and arranged with its mechanical parts similar for use in sharpening different kinds 25 of safety razor blades, a change of construction being made necessary only to adapt the machine to different types of blades, of the double edge or single.

One embodiment of the invention is here- 30 in described and illustrated in the accom- panying drawings, in which—

Figure 1 is a plan of the machine with the top of its case removed to show the operating mechanism of the machine.

Fig. 2 is a vertical section on the plane indicated by line 2—2 of Fig. 1.

Fig. 3 is a vertical section on the plane indicated by line 3—3 of Fig. 1.

Fig. 4 is a vertical section on the line 4—4 of Fig. 1 showing the slides at extreme positions.

Fig. 5 is a horizontal cross section on the line 5—5 of Fig. 4.

Fig. 6 is a section similar to Fig. 4 showing the slides in the intermediate positions and showing the razor blade tilted for engagement with the strop blocks.

Fig. 7 is an elevation and partial section of a mandrel and barrel construction adapted for use with single edge blades having reinforced back edges.

Fig. 8 is a longitudinal section of the device of Fig. 7 taken at a plane at right angles to the blade shown in Fig. 7.

Fig. 9 is a perspective of the mandrel 55 shown in Fig. 7.

The machine consists of suitable mechanism as will be hereinafter described, preferably substantially all contained in a simple and substantial shell or box of generally oblong form having end walls 2—2, bottom 3, side walls 4—4 and a removable top or cover section 5 which has end flanges telescopic in the end walls and side flanges 6—6 which, with the upper ends of the side walls 4 are provided with semicircular recesses 7 combining to form a journal for a crank shaft 8 having an outwardly extending crank 9 on one end exposed beyond the side wall to be manually, or otherwise, if 70 desired, rotated.

Upon the inner faces of the end walls 2 are provided guides shown as tracks 10 extending from just below the removable cover 5 down to the bottom 3. The tracks are 75 arranged in pairs with the tracks in opposed position on opposite end walls and they are shown as having oblique running faces 10' with respect to the planes of the walls 2. Slidably mounted upon the tracks of each 80 pair is a slide 11 having flange portions 11' complementary to the guide tracks 10. There is provided therefore a pair of the slides 11 and these are disposed with parallel faces to which are secured in any suitable manner abrasive sheets or blocks, for instance blocks 12 of leather, such as is commonly used for the sharpening of razor 85 blades. The blocks are presented with plane abrasive surfaces suitably spaced apart, and in this space there is arranged a transversely 90 extending hollow shaft or barrel, as will be explained below.

Upon the backs of the slides 11 are provided pins 11^a and these are engaged by 95 the lower ends of connecting links 13 whose upper ends are mounted upon respective cranks 8' of the crank shaft 8; the cranks 8' being shown as offset along the shaft and on opposite sides thereof so that the 100 slides move in opposite directions to each other during rotation of the crank shaft.

The barrel, above referred to, is shown as in the form of a sleeve 14, the ends of which are journaled in the end walls 2 of 105 the box, and one end is shown as riveted over as at 14', while inside of the case the same end is provided with a collar 14^a for

the purpose of preventing axial movement of the barrel 14 but permitting its free rotation.

As shown in Fig. 3, one end of the barrel 14 is arranged in an elongated slot 15 in one end wall 2 and the barrel is longitudinally slotted from its end in the slot or blade hole 15 to the collar 14^a. This permits the insertion of a mandrel 16 which is of a size to slide into the barrel 14 and carry with it a blade B which is to be sharpened. The blade B is of the double edged type and is provided with a series of apertures b arranged in a row along its longitudinal axis, and it is retained upon the mandrel 16 by means of a set of lugs 16' provided along a plane face of the mandrel, which latter is of semicylindrical form, the plane face lying along the axis 20 of the mandrel. At one end of the mandrel there is provided a shoulder 16^a and this is adapted to engage a stop pin 14^b provided inside of one wall of the barrel 14 and the purpose of which is to prevent the entire withdrawal of the mandrel 16 when it is pulled outwardly from the barrel by the application of the fingers to a thumb head 16^b on the outer end of the mandrel.

From this it will be seen that when the mandrel is pulled to the outer position the lugs 16' thereof are exposed and a blade B can be applied, and when this is registered with the blade receiving aperture 15 then the mandrel is pushed inwardly carrying with it the blade B which will project through the diametrically opposite slots along the top and bottom of the split barrel 14.

Means are provided for oscillating the barrel so as to throw the opposite edges of the blade B from side to side so as to alternately engage with the oppositely moving stropping blocks 12 on the slides 11. A simple and practicable form of barrel oscillating means is shown as consisting of a cam groove 19 formed upon the crank shaft 8 between the offset cranks 8' thereof, the cam groove being of continuous form and disposed in a diagonal position as to the axis of the crank shaft. The walls of the groove are engaged by a pin 20 extending at right angles from the axis of the crank shaft 8 and being fixed on the upper arm 21 of the lever having a lower arm 22, and which lever is pivoted at 23 upon one of the end walls 2, as shown in Figs. 4 and 5. The lower end of the arm 22 of the lever is provided with a segmental gear 24 and this in turn constantly meshes with a segmental pinion 25 which may form a peripheral portion of the hub 14^a of the barrel 14. The arrangement of the cam groove 19 with respect to the cranks 8' of the crank shaft is such that when the slides 11 are in their extreme positions in the box or shell, as

shown in Fig. 4, then the lever 21 and 22 stands in its intermediate position and is substantially parallel to the slides 11 and so holds the blade B in an intermediate position, whilst the cranks in passing their cycles start a reverse movement of the slides. When the slides have started upon their strokes, the blade is drawn so that one side of one of its edges engages the stropping block 12 moving away from the contiguous edge or moving upwardly as shown in Fig. 6, while at the same time the opposite edge and opposite side of the blade is engaging the downwardly moving stropping block. As the slides approach and pass their extreme positions, the blade is again oscillated by the cam device and its edges are drawn to engage stropping blocks which will engage the opposite sides of the razor edges. In other words, the edges are each subjected to alternate engagement at opposite sides with the respective stropping blocks.

It is desirable that means be provided for preventing the stropping blocks from moving in a direction toward the sharp edges of the blade, and any suitable means may be utilized for this purpose. As shown in Fig. 3, a toothed dog 26 is pivoted to one side of the crank shaft and is designed to engage a circular hub 27 provided thereon when the crank shaft is rotated backwardly, but which dog allows the crank shaft to be rotated in one or the forward direction.

The slides 11 with their stropping blocks 12 are preferably moved with an oblique line of travel with respect to the edges of the blade, as is indicated in Fig. 2.

It is understood that the machine, as above described, is made standard for the sharpening of razor blades of the type shown at B, and when it is desired to utilize the machine as standard for the sharpening of other types of blades, as for instance the type of blade shown at B², Fig. 7, then the mandrel 16 is of somewhat different construction but the sleeve 14 remains as previously described. The blade B² is of the type having one edge sharpened and having a backing or reinforcing strip b'. To accommodate this kind of blade the mandrel 16 is provided with a longitudinally extending resilient receiver 30 with an open mouth disposed along the body of the mandrel and from which mandrel the receiver extends radially. The stiffening back b' of the blade B² is adapted to be forced into the open mouth of the receiver 30 in which the blade will be frictionally held.

Various changes and modifications may be made without departing from the spirit of the invention as claimed.

What is claimed is:

1. A machine for sharpening safety razor blades comprising fixed guides having slides

with stropping faces, means for reciprocating the slides concurrently in reverse motions, and means for holding a blade between and alternately moving the blade against the slides.

2. A machine for sharpening safety razor blades comprising a shell having on inside wall faces fixed guides, parallel slides with stropping faces, means for reciprocating the slides concurrently in reverse motions on the guides, and means for holding a blade between and alternately moving the blade against the slides.

3. A machine for sharpening safety razor blades comprising slides with stropping faces, means for reciprocating the slides concurrently in reverse motions, means for holding a blade between and alternately moving the blade against the slides, and guides upon which the slides move in paths oblique to the engaged blade edge.

4. A machine for sharpening safety razor blades comprising a shell having fixed guides, slides with stropping faces sliding on said guides, means for reciprocating the slides concurrently in reverse motions in the shell, and means for holding a blade between and alternately moving the blade edges from slide to slide, the said slides being arranged to act upon two parallel edges of the blade concurrently.

5. A machine for sharpening safety razor blades comprising a shell, a plurality of opposed stropping slides slidably mounted on the shell walls, a blade holder arranged between opposed faces of the slides to move the blade to engage the same, means for oscillating the blade holder, and a means, common to the slides and to the said holder for actuating the same.

6. A machine for sharpening safety razor blades comprising a plurality of opposed stropping slides, a blade holder arranged between opposed faces of the slides, means for oscillating the blade holder to carry a blade against said slides, and a means, common to the slides and to the said holder for actuating the same, and including a shaft connected to the slides and having a cam for actuating the holder.

7. A machine for sharpening safety razor blades comprising a plurality of opposed stropping slides, a blade holder arranged between opposed faces of the slides, means for oscillating the blade holder, and a means, common to the slides and to the said holder for actuating the same, and including a crank shaft connected to the slides and having a cam for actuating the holder.

In testimony whereof I have signed my name to this specification.

JOSEPH B. RUATTI.
